FRANCIS F. HAMILTON, OF INDIANAPOLIS, INDIANA.

DESIGN FOR A BOX.

Application filed December 4, 1926. Serial No. 19,926. Term of patent 7 years.

To all whom it may concern:

Be it known that FRANCIS F. HAMILTON, a citizen of the United States, residing at Indianapolis, in the county of Marion and State of Indiana, has invented a new, original, and ornamental Design for a Box, of which the following is a specification, reference being had to the accompanying drawing, forming a part thereof.

Referring to the drawing—

Fig. 1, is a front perspective view of a box

showing my new design, and Fig. 2, is a view in side elevation of same.

The dominant feature of the design is a closed cedar chest supported between conventional or simplified head and tail ends suggestive of a cat.

I claim:—

The ornamental design for a box, as shown and described.

In testimony whereof I affix my signature.

FRANCIS F. HAMILTON.
